TRUING APPARATUS FOR LAPPING MACHINES

Herbert S. Indge, Westboro, Mass., assignor to
Norton Company, Worcester, Mass., a corpora-
tion of Massachusetts

Application September 28, 1935, Serial No. 42,583

7 Claims. (Cl. 125—11)

This invention relates to lapping or grinding machines, and more particularly to a lap or grinding wheel truing mechanism.

One of the objects of this invention is to provide a simple, thoroughly practicable truing apparatus for truing the flat operative face of a lap or abrasive wheel. Another object is to provide a truing apparatus for truing the opposed operative flat faces of two opposed lapping or grinding wheels. Another object is to provide a truing apparatus which is capable of truing the two opposed operative faces of a pair of opposed lapping or grinding elements simultaneously.

A further object is to provide a pivotally mounted truing tool carrier for swinging the truing tool or tools through an arcuate path across the operative face or faces of a lap or grinding wheel. Another object of this invention is to provide a pivotally mounted truing tool holder which is rocked through an arcuate path across the face of the grinding wheel by a hydraulically actuated mechanism.

A further object is to provide a hydraulically actuated mechanism for controlling the movement of a truing tool across the face of a lap or grinding wheel, in which the truing speed may be readily controlled. A further object is to provide a hydraulically actuated mechanism for moving a truing tool through an arcuate path across the operative face of a lap, in which both the intake and exhaust of fluid are throttled to definitely control the rate of movement of the truing tool. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

Fig. 1 is a side elevation of a lapping machine and truing apparatus embodying this invention, having parts broken away to more clearly show the construction;

Fig. 2 is a fragmentary cross-sectional view, on an enlarged scale, taken approximately on the line 2—2 of Fig. 1;

Fig. 3 is a combination cross-sectional view and elevation of the mount for the truing apparatus taken approximately on the line 3—3 of Fig. 2;

Fig. 4 is a fragmentary elevation, on an en-

larged scale, of the pivotal support for the truing apparatus;

Fig. 5 is a cross-sectional view, on an enlarged scale, taken approximately on the line 5—5 of Fig. 1;

Fig. 6 is a fragmentary cross-sectional view, on an enlarged scale, taken approximately on the line 6—6 of Fig. 1, of the binder mechanism for locking the upper lapping element in any desired position;

Fig. 7 is a cross-sectional view through the control valve, on an enlarged scale, taken approximately on the line 7—7 of Fig. 2;

Fig. 8 is a cross-sectional view, on an enlarged scale, taken approximately on the line 8—8 of Fig. 2;

Fig. 9 is a vertical section showing a modified form of mounting for the truing tools;

Fig. 10 is a cross-sectional view, taken approximately on the line 10—10 of Fig. 9, showing the clamping mechanism for the truing tools; and

Fig. 11 is a fragmentary cross-sectional view taken approximately on the line 11—11 of Fig. 9, showing the adjusting mechanism for the truing tools.

In the embodiment of the invention selected for illustration, a lapping machine has been shown comprising a base 11 adapted to support a lower lap 12 and an upper lap 13. The upper and lower laps are arranged for a relative rotary motion to produce a predetermined lapping operation. In the preferred construction, both the upper and the lower laps are rotated preferably in different directions.

Power may be supplied to the machine in any convenient manner, such as by means of a belt arranged to rotate a pulley 15 keyed to a shaft 16 journaled in bearings 17, 18, 19, and 20 in the base 11 of the machine and arranged to rotate both the upper and the lower lap. A worm 21 is fastened to the shaft 16 and meshes with a worm gear 22 keyed to a vertical sleeve 23 which is rotatably supported in a bearing 24 within the base of the machine. The upper end of the sleeve 23 supports a spider 25 which in turn supports the lower lapping wheel 12. The rotary motion applied to pulley 15 is transmitted through shaft 16, worm 21, worm gear 22, sleeve 23 and spider 25 to rotate the lower lap 12. The details of the mounting for the upper lap have not been shown in detail in the present case, since they are not considered to be a part of the present invention. For further details, reference

may be had to my prior Patent No. 1,870,328 dated August 9, 1932.

The lapping elements or wheels 12 and 13, as illustrated, are each formed as an annulus of ceramic bonded abrasive grains made like a grinding wheel, each of which is provided with a substantially flat abrading or lapping surface for simultaneously engaging and abrading or lapping the opposed faces of a work piece.

10 The rotatable upper lap 13 is supported by means of a spider 30 mounted on the lower end of a rotatable spindle 31. The spindle 31 is rotatably supported in bearings (not shown) in a vertically movable sleeve 32 which is slidably mounted within a projecting portion 34 of an arm 35. The arm 35 is formed integrally with a vertically extending column 36 which is fixed to the base 11. The lap 13 and spindle 31 may be rotated from any suitable source of power, 15 but as illustrated in the drawings is driven by means of a belt from the shaft 16. A pulley 40 is mounted on the shaft 16 and is connected by means of a belt 41 with a pulley 42 mounted on the upper end of the upper lap spindle 31. The 20 belt 41 passes over a pair of idler pulleys 43 (only one of which has been illustrated in Fig. 1) which are rotatably supported on a transverse shaft 44. It will be readily apparent from the foregoing disclosure that rotation of the shaft 16 by means 25 of driving pulley 15 serve to simultaneously rotate both the upper lap 13 and the lower lap 12.

In order that the laps 12 and 13 may be maintained with proper operative surfaces for producing the desired lapping operation, a suitable 30 truing apparatus is essential to permit a truing of the operative faces of the laps when necessary. In the embodiment of the invention illustrated, a pivotally mounted truing apparatus is provided in which a truing tool is mounted on a rock arm 40 and arranged to be swung through an arcuate path across the operative face or faces of the lap. As illustrated in the drawings, this mechanism comprises a vertically mounted rotatable shaft 50 supported in bearings 51 and 52 on a bracket 53 which is rigidly mounted on the columns 36. An arm 54 is mounted on the shaft 50. The arm 54 is provided with an elongated head 55 which is slotted at 56 and arranged to be clamped in adjusted position on the shaft 50 by means of clamping screws 57 and 58. The screws 57 and 58 pass through clearance holes in bosses 59 and 60 and are screw threaded into bosses 61 and 62 so that the head 55 may be readily clamped in adjusted position on the vertical shaft 50. A push screw 65 is screw threaded in a boss 66 and abuts against a boss 67. This push screw serves to spread or expand the head 55 when it is desired to unclamp the arm 54. An end thrust and locating collar 70 serves to locate the head 55 in the desired position on the shaft 50. The collar 70 is preferably a split collar and arranged to be clamped in adjusted position on the shaft 50 by means of a clamping screw 71. The shaft 50 is rotatably mounted in bearing brackets 51 and 52 which are fixedly mounted on the column 36. A thrust washer or collar 75 which fits on a reduced portion 76 on the lower end of the shaft 50 and bears against the upper surface of bearing 52 serves to take up the vertical thrust of the shaft 50 and its associated parts. A similar collar or thrust washer 77 also fits on the reduced portion 76 and is held in adjusted position by a pair of lock nuts 78 and 79. The thrust collars 75 and 77 together with the lock nuts 78 and 79 serve as an end thrust bearing

to hold the shaft 50 in the desired vertical position.

The outer end of the arm 54 is provided with an enlarged head 80 which is arranged to support a pair of opposed diamonds or truing tools 81 and 82, each of which is separately adjusted relative to the head 80. The truing tool 81 is mounted in the end of a spindle 83 which is slidably keyed by means of key 84, in an aperture 85 within head 80. An adjusting screw 86 is screw threaded into a threaded aperture 87 in the spindle 83 and serves to adjust the position of the spindle 83 and the truing tool 81 relative to the head 80. In order that the screw 86 may be held against endwise movement, it is provided with an enlarged head 88 which fits within a counterbored recess 89 in the head 80 and is held in adjusted position relative thereto by means of a cap or cover plate 91. The diamond or truing tool 82 is held in a similar spindle 95 which is slidably keyed by means of a key 96 within an aperture 97 within the head 80 and is arranged to be adjusted relative thereto by means of a screw 98 which is screw threaded into a threaded aperture 99 within the spindle 95. The screw 98 is provided with an enlarged head 100 which fits within a counterbored aperture 101 in the head 80 and is held in adjusted position therein by means of a cover plate 102. It is readily apparent from the foregoing disclosure that the diamonds or truing tools 81 and 82 may each be adjusted relative to the head by manipulation of screws 86 and 98.

In order that the diamonds or truing tools may be locked in adjusted positions on the head 80, the opposite sides of the head are provided with slots 105 and 106 which enable portions of the head to be sprung to bind the spindles 83 and 95 in their adjusted position. A binding screw 107 passes through a clearance hole in a boss 108 and is screw threaded into a boss 109 to clamp the spindle 83 and diamond 81 in the desired adjusted position. A binding screw 110 passes through a clearance hole in boss 111 and is screw threaded into boss 112 to serve as a clamp for the spindle 95 and the diamond 82 in the desired adjusted position. It will be readily apparent from the foregoing disclosure that the diamonds 81 and 82 may be readily and precisely adjusted relative to the head 80 by manipulation of the clamping screws 107 and 110 and the adjusting screws 86 and 98.

To attain one of the objects of this invention, it is desirable to provide a suitable power operated mechanism for moving the truing tools across the face of the laps 12 and 13 at a slow uniform rate to true the operative faces thereof to form the desired lapping surfaces. In the preferred construction, a hydraulically actuated mechanism is provided to swing the arm 54 to pass the truing tools 81 and 82 through an arcuate path across the operative flat faces of the lapping wheels. A fluid pressure cylinder 120 is pivotally mounted on a stud 121 which is in turn supported in a bracket 122 projecting from the column 36. A piston 123 is slidably mounted within the cylinder 120 and is connected by means of a piston rod 124 with a stud 125. Stud 125 is also connected with one end of a connecting rod 126, the other end of which is pivotally connected to a stud 127. The stud 127 is connected to one end of a rock arm 129, the other end 130 of which is locked to the upper end of the shaft 50 by means of a set screw 131. It will be readily apparent from the foregoing disclosure that when

fluid is admitted to the cylinder 120, causing the piston 123 to move therein, this motion will be transmitted through the connecting rod 124, stud 125, connecting rod 126, to rock the arm 129 which in turn serves to rock the vertical shaft 50 and thereby swing the arm 54 and the truing tools 81 and 82 across the operative faces of the laps 12 and 13.

A fluid pressure system is provided to supply fluid under pressure to operate the piston 123. This system comprises a reservoir 115 within the base of the machine. A pump 116 draws fluid from the reservoir 115 through a pipe 132 and forces fluid under pressure through a pipe 133 to a control valve 134. A pressure relief valve 135 is connected in the pipe line 133 to return excess fluid through an exhaust pipe 136 to the reservoir 115. The control valve 134 is of a slidable piston type and comprises valve pistons 138, 139, 20 and 140 which are formed integrally with a valve stem 141. This valve serves as a reversing valve and also a speed control or throttle valve to control the direction and speed of movement of the truing tool or tools across the operative 25 faces of the laps. Fluid under pressure from the pipe 133 enters a valve chamber 142 formed between the valve pistons 138 and 139 and passes out through a pipe 143 into a cylinder chamber 144 to cause the piston 123 to move toward the 30 right, as viewed in Fig. 2, which serves to rock the arm 54 in a counterclockwise direction. During this movement of the arm 54, fluid under pressure exhausts from a cylinder chamber 145, a pipe 146, a valve chamber 148 formed between 35 valve pistons 139 and 140 and out through an exhaust pipe 149 and through the pipe 136 into the reservoir 115.

The valve stem 141 is provided with an operating knob or handle 150. When it is desired to 40 reverse the direction of movement of the arm 54 so as to cause the truing tools to move in a clockwise direction (Fig. 2), the knob 150 is moved into a position 150a, as shown in broken lines in Fig. 2, which serves to shift the valve pistons 138, 139, 45 and 140 into a reverse position so that fluid under pressure from the pipe 133 will pass through valve chamber 148 between the valve pistons 139 and 140 and through pipe 146 into a cylinder chamber 145 to cause the piston 123 to move toward the 50 left, as viewed in Fig. 2, so as to swing the arm 54 and the truing tools 81 and 82 in a clockwise direction through an arcuate path across the operative faces of the laps 12 and 13. During this movement of the piston 123, fluid 55 under pressure exhausts from the cylinder chamber 144 through the pipe 143, the valve chamber 142 between the pistons 138 and 139, and out through a pipe 152 and the pipe 136 to the reservoir 115.

In order that the laps 12 and 13 may be trued 60 to produce the desired lapping surface, it is desirable to provide a speed controlling device for the fluid pressure system so that a slow uniform traverse of the truing tool across the face of the laps may be obtained. This is preferably accomplished by providing a suitable arrangement for throttling the fluid passing through the control valve 134. In the preferred construction, the valve 134 is provided not only with a longitudinal 65 motion to cause a reversal of the direction of flow of fluid within the system but is also provided with a rotary motion which serves to throttle the flow of fluid through the valve. The valve is so constructed that both the intake and exhaust of fluid are throttled to the same extent 70

to provide a slow uniform movement of the truing tool.

The valve stem 141 is provided with a serrated portion 155 which is engaged by a spring pressed plunger 156 so that the valve stem 141 may be readily rotated to the desired position and held in the adjusted position. In order to throttle the fluid passing to and from the control valve, the valve pistons 138 and 140 are each provided with throttling grooves 160 (Figs. 2 and 8). 10 There are four openings or holes 159 through the valve sleeve 161 and four grooves 160 which extend longitudinally of the valve piston 140 forming lands 165 therebetween. By rotating the valve stem 141, the lands 165 between the grooves 15 160 may close the valve sleeve openings 159 to a greater or lesser extent to throttle the flow of fluid therethrough. Fig. 8 shows a cross section through the valve taken on the line 8—8 of Fig. 2 through the valve piston 140. The valve 20 piston 138 is similarly provided with grooves and lands so that the fluid entering or exhausting from the valve chamber 142 may also be throttled to the same extent. It will be readily apparent from the foregoing disclosure that by 25 endwise movement of the valve stem 141, the fluid under pressure within the system may be reversed to move the piston 123 in either direction so as to move the truing tools either in a clockwise or counterclockwise direction 30 across the face of the laps to be trued. By rotating the knob 150 and valve stem 141, the fluid entering or exhausting from the system may be varied from the maximum to a point where the fluid is entirely cut off, that is when the 35 lands 165 (Fig. 8) are turned to entirely block the ports 159 in the valve sleeve 161. By rotating the valve stem to the desired extent, the speed of movement of the truing tools may be accurately controlled to produce the desired lapping surface.

It may be desirable to arrange the truing tools 81 and 82 in axial alignment and diametrically opposed to each other so that both of the laps 12 and 13 may be simultaneously trued. A modified construction has been illustrated in Figs. 9, 10, and 11, in which the truing tools 81 and 82 are arranged diametrically opposite to each other. The arm 54, as shown in Figs. 9, 10, and 11, is provided with an enlarged head 191 having a 45 vertically extending aperture 192 arranged to receive a pair of diamonds or truing tool holders 193 and 194. The truing tool holder 194 is provided with a reduced threaded portion 195 which engages or meshes with a threaded aperture 196 50 within the diamond holder 193. A pair of binding screws 197 and 198 are arranged to bind the diamond holders 193 and 194 in place on the head. Details of only one of the clamping mechanisms have been illustrated since they are both 55 identical in construction. As shown in Fig. 10, the clamping screw 197 passes through a clearance hole in a slidably mounted bushing 200 and is screw threaded into a central aperture within the slidably mounted bushing 201. The bushings 60 200 and 201 are each provided with a transversely extending fragmentary cylindrical surface 202 and 203 respectively which are shaped to mate with the periphery of the truing tool holder 193 and 194 respectively. It will be readily apparent from the above disclosure that when the screw 197 is tightened, the bushings 200 and 65 201 are drawn together to clamp the diamond holder 193 in adjusted position.

In order that the truing tools 81 and 82 may 70

75

be readily and separately adjusted, the inner ends of the truing tool holders 193 and 194 are formed as a spiral gear 205 and 206 respectively. A pair of spiral gears 207 and 208 mesh with the gears 205 and 206 respectively. Gears 207 and 208 are mounted on rotatable shafts 209 and 210 respectively and are arranged to be adjusted by knobs 211 and 212 respectively. The binding screws 197 and 198 are maintained in a clamped position except during adjustment of the diamonds 81 and 82. If it is desired to adjust the diamond 82, the clamping screw 198 is loosened to unclamp the holder 194 while the clamping screw 197 is in a clamped relationship to hold the diamond holder 193 against rotation. Then the knob 212 is turned to rotate the shaft 210, spiral gear 208, spiral gear 206, which serves to rotate the diamond holder 194. This movement rotates the screw 195 within the threaded aperture 196 and due to the fact that the holder 193 is stationary serves to cause an endwise movement of the holder 194 to adjust the diamond 82 as desired.

Similarly, when it is desired to adjust the position of diamond 81, the clamping screw 198 is locked in a clamping position to prevent rotation of the holder 194. The clamping screw 197 is unclamped to permit rotation of the holder 193 and the adjusting knob 211 is rotated to cause a rotation of the spiral gear 207 which serves to rotate spiral gear 205 and thereby cause a rotation of the diamond holder 193. Due to the fact that the threaded projection 195 is held stationary, the threaded aperture 196 is rotated on a fixed threaded portion 195 and causes an endwise motion of the holder 193 to adjust the diamond 81 as desired.

40 The upper lap 13 is arranged to be moved vertically with relation to the lower lap. This may be accomplished either by means of a manually controlled or automatically controlled mechanism. For the sake of simplicity of illustration, a manually operable mechanism has been provided comprising a hand wheel 170
45 which is mounted on the outer end of a shaft 171, the inner end of which carries a gear 181 meshing with a rack bar 182 on the vertically movable sleeve 32. By manipulating the hand wheel 170, the upper lap may be raised or lowered
50 as desired. This mechanism serves to bring the upper lap into operative relation with the work during thelapping operation and also serves to lower the lap until the operative face of the lap engages the truing tool for a truing operation.

55 In order that the upper lap may be held against vertical movement in a fixed position during the truing operation, means are provided to lock the sleeve 32 in an adjusted truing position. This mechanism comprises a clamping screw 185
60 which comprises two slidably mounted bushings 186 and 187 each of which is provided with a partial cylindrical surface 188 and 189 respectively, which engage the periphery of the sleeve 32. The clamping screw 185 passes through a clearance hole in the bushing 186 and is screw threaded into an aperture 190 in the bushing 187. By tightening the screw 185, the bushings 186 and 187 are drawn together to clamp the sleeve 32 in rigid engagement with the projection 34 of the arm 35 so as to lock the upper lap in a truing position. Truing tool 81 may then be oscillated through an arcuate path across the operative face of the lap 13 by oscillating the arm 54 by means of a fluid pressure mechanism.

75 In the operation of this truing apparatus, the

arm 54 is adjusted vertically on the shaft 50 and clamped in adjusted position by means of the locating collar 70 and the arm is then clamped in position thereon by means of the clamping screws 57 and 58. The lap 12 is then set in rotation and the valve 134 operated by means of the knob 150 serves to pass the truing tool 82 across the operative face of the lower lap. By adjusting the screw 98, the truing tool 82 may be brought into the desired truing relation with the operative face of the lap 12. The truing tool may then be oscillated through an arcuate path across the face of the lap until the lap is trued to the desired extent. By adjusting the position of the truing tool, any amount of material may be trued from the lap as desired.

To true the upper lap 13, the hand wheel 170 is rotated to turn the gear 181 which meshes with the rack bar 182 on vertically movable sleeve 32. By manipulating the hand wheel 170, the upper lap 13 may be lowered until the operative face of the lap engages the truing tool 81. The sleeve 32 may then be locked in a truing position by means of the clamping screw 185. The truing tool 81 may then be oscillated 25 through an arcuate path across the operative face of the lap 13 by oscillating the arm 54 by means of the fluid pressure mechanism. By turning the adjusting screw 86, the diamond or truing tool 81 may be precisely adjusted relative to the 30 lap 13 to true its operative surface to the desired extent.

In the operation of the modified construction, the truing tool supporting arm 54 is moved so that the diamond 82 is opposite to the lap 12. 35 The diamond 82 is then adjusted downwardly to contact with the surface of the lap 12. The upper lap 13 is then lowered by manipulation of the hand wheel 170 so that the operative surface of the lap 13 is brought into truing engagement with the truing tool 81. Then, by manipulation of the fluid pressure mechanism, the truing tools may be passed through an arcuate path relative to the laps 12 and 13 to simultaneously true the opposed operative surface of 40 45 the two laps.

the two laps.

It will thus be seen that there has been provided by this invention apparatus in which the various objects hereinabove set forth together with many thoroughly practical advantages are successfully achieved.

As many possible embodiments may be made of the above invention and as many changes might be made in the embodiment above set forth, it is to be understood that all matter hereinbefore set forth, or shown in the accompanying drawings, is to be interpreted as illustrative and not in a limiting sense.

I claim:—

1. An abrasive wheel truing apparatus comprising a rotatable abrasive wheel, a movable truing tool support, a truing tool adjustably mounted thereon, means to feed the truing tool relatively toward and from the operative face of said abrasive wheel, means including a fluid pressure piston and cylinder to move said support to pass the truing tool across the operative face of said wheel, and a control valve for regulating both the direction and speed of movement of the truing tool relative to the operative face of said abrasive wheel. 60 65 70

race of said abrasive wheel.

2. A truing apparatus for a lapping machine comprising a rotatable lapping wheel having an operative flat face, a movable truing tool support, a truing tool adjustably mounted thereon. 75

means to adjust the truing tool to feed the tool toward and from the operative face of said lapping wheel, means including a fluid pressure piston and cylinder to move said support and traverse the truing tool across the operative face of said lap, and a single control valve therefor, said valve being movable in one direction to control the direction of movement of the truing tool and movable in a second direction to control the speed of movement of the truing tool relative to said lap.

3. A truing apparatus for a lapping machine comprising a rotatable lapping wheel, a pivotally mounted truing tool support, a truing tool adjustably mounted thereon, means to adjust the truing tool relative to the support to permit feeding the truing tool toward and from the operative face of said lapping wheel, means including a fluid pressure piston and cylinder to swing the support so as to traverse the truing tool across the operative face of said lap, a fluid control valve therefor, and a manually operable means to move said valve in one direction to change the direction of movement of the truing tool relative to the lap and to move said valve in a second direction to hold it in a predetermined position to regulate the speed of movement of the truing tool relative to the operative face of the lap.

30 4. A truing apparatus for a lapping machine comprising a rotatable lapping wheel having an operative flat face, a movable truing tool support, a vertical pivot for said support, a truing tool adjustably mounted thereon, means to adjust the truing tool to feed the truing tool toward and from the operative face of the lapping wheel, means including a fluid pressure piston and cylinder to swing said truing tool across the face of said lap, a single control valve therefor, and means to move said valve longitudinally in one direction to reverse the movement of the truing tool and to rotate and hold said valve in a predetermined position to control the speed of movement of the truing tool across the operative face of said lap.

45 5. A truing apparatus for a lapping machine

comprising a rotatable lapping wheel, a pivotally mounted truing tool support, a truing tool adjustably mounted thereon, means to adjust the truing tool to feed the tool toward or from the operative face of the lap, means including a fluid pressure piston and cylinder to move said support to traverse said tool across the face of said lap, a control valve therefor, and means to move said valve longitudinally to reverse the direction of movement of the truing tool relative to the lap and to rotate and hold said valve in a desired rotary position to throttle both the intake and exhaust of fluid to and from said cylinder to control the speed of movement of the truing tool relative to the operative face of said lap.

15 6. A truing apparatus for a lapping machine comprising a pair of opposed flat relatively rotatable lapping wheels, a movably mounted truing tool support, a pair of opposed truing tools adjustably supported thereon, means to independently adjust each of said tools relative to the support, means including a fluid pressure piston and cylinder which are operatively connected to move said support to simultaneously traverse the truing tools across the operative faces of said lapping wheels, and a control valve for regulating both the direction and speed of movement of the truing tools relative to the operative faces of said lapping wheels.

20 7. A truing apparatus for a lapping machine comprising a pair of opposed flat relatively rotatable lapping wheels, a movably mounted truing tool support, a pair of opposed truing tools adjustably supported thereon, means to independently adjust each of said tools relative to the support, means including a fluid pressure piston and cylinder which are operatively connected to move said support to simultaneously traverse the truing tools across the operative faces of said wheels, and a control valve in said system which serves when moved in one direction to reverse the direction of movement of the truing tool and when rotated serves to throttle the fluid under pressure to control the speed of movement of the truing tools across said lap.

35 40 45 HERBERT S. INDGE.
